UNITED STATES PATENT OFFICE.

HENRY F. MUELLER, OF ALTENBURG, MISSOURI.

MAIL-HOLDING DEVICE.

1,097,184.

Specification of Letters Patent.

Patented May 19, 1914.

Application filed May 21, 1912. Serial No. 698,785.

To all whom it may concern:

Be it known that I, HENRY F. MUELLER, a citizen of the United States, residing at Altenburg, in the county of Perry and State 5 of Missouri, have invented certain new and useful Improvements in Mail-Holding Devices; and I do hereby declare the following to be a full, clear, and exact description of the invention, such as will enable others 10 skilled in the art to which it appertains to make and use the same.

My invention relates to new and useful improvements in mail holding devices.

The object of my invention is to provide 15 a device adapted to be suspended upon the inside of the usual or any preferred form of mail box to hold the letters or packages placed in said device.

Other objects and advantages will be hereinafter made clearly apparent in the specification and pointed out in the claim.

In the accompanying drawings I have shown the preferred form which my invention may take.

25 In said drawings, Figure 1 is a perspective view showing my invention secured in place in a mail box. Fig. 2 is an elevation showing my device detached. Fig. 3 is a detail sectional view, as seen on line 3—3, Fig. 2.

30 Referring to the drawings, in which similar reference numerals designate corresponding parts throughout the several figures, 6 is a mail box, which has its forward side open and adapted to be normally closed by means 35 of a door 7.

My improved mail holding device is adapted to be suspended from the upper end of a box 6 by means of a loop 8, which is secured to the upper end of the box in any 40 preferred manner.

45 My device is preferably formed of a single strip of spring metal and is bent at its center to form a loop 9 and the ends 10 and 11 of said strip are extended converging toward one another part way and contacting for the balance of their lengths and the extreme ends bent back upon the strip to form finger receiving loops 12 by means of which the ends of the device may be pulled apart when it is 50 desired to insert letters between them. The device is so formed that the ends of the strip press tightly against each other so that when

an object such as a letter or package is placed between them, it will be held in place. The sides of the contacting portions of the ends 55 of my device are bent outwardly, as clearly shown at 16 in the drawings, for a purpose to be hereinafter clearly set forth.

A spring 15, which is formed from a single strip or spring wire, is bent in the form of a 60 helical spring and disposed in the looped end 9 of my device and the ends are extended along the inner sides of the ends 10 and 11, the extreme ends of said spring being bent around opposite sides of said ends 10 and 11, 65 in opposite directions and by this construction the displacement of said spring from the loop in either direction will be effectually prevented.

70 My invention is particularly desirable for use in mail boxes to be used upon rural routes, where the same box is employed for sending and receiving letters. The owner of the box, when sending letters, may separate the ends of the device by means of the finger 75 loops 12 and insert his letter or letters therebetween, or may force the letters therebetween without touching the device with his hand. The device will hold the letters suspended and, when the carrier opens the box, 80 it is only necessary for him to catch the letter or letters and pull them from between said ends. Any mail which he desires to deliver will be thrown in the box on the bottom. Should the person to whom the letters 85 are addressed not take the same from the box until the carrier's second trip, the carrier would not be confused and have to look over the addresses of the letters to see if the same were to be taken by him, as he would know 90 that the mail to be taken by him would be suspended and not left upon the floor of the box. By bending the sides of the engaging portion of the device outwardly, as shown at 16, there will be no danger of tearing the 95 envelops or stripping off or mutilating the stamps thereon.

What I claim as new is:

A holding device consisting of a resilient metal strip bent in the form of a loop with 100 gripping arms extending therefrom, converging toward each other for a portion of their length and contacting with each other near their ends, and a helical spring in said

loop having its respective ends extended against the inner faces of the arms and the terminals thereof bent in opposite directions around the opposite side edges of the arms to 5 hold the spring against displacement from either end of the loop.

In testimony whereof I have signed my

name to this specification in the presence of two subscribing witnesses.

HENRY F. MUELLER.
